United States Patent Office

Des. 232,893
Patented Sept. 24, 1974

232,893

SHELF MODULE

Billy Moretini, Chicago, Ill., assignor to International Design Corporation, Chicago, Ill.

Original design application Nov. 10, 1971, Ser. No. 197,643, now abandoned. Divided and this application May 30, 1973, Ser. No. 365,160

Term of patent 14 years

Int. Cl. D6—04

U.S. Cl. D6—189

FIG. 1

FIG. 2

FIG. 1 is a perspective view of a shelf module showing my new design; and

FIG. 2 is a perspective view of a shelf module showing a modified form of my new design.

The unseen rear elevational views of the modules illustrated in FIGS. 1 and 2 are respectively the mirror images of the visible front elevational views of these figures. The unseen bottom and right hand side walls of the modules illustrated in FIGS. 1 and 2 are substantially flat and plain corresponding respectively to the configuration shown on the outer top and left hand side walls of the modules.

This is a division of application Ser. No. D. 197,643, filed Nov. 10, 1971, now abandoned.

I claim:

The ornamental design for a shelf module, as shown and described.
